C. A. Jones, Esq.

UNITED STATES PATENT OFFICE.

THOMAS SURTEES, OF MIDDLEPORT, OHIO.

WAGON-JACK.

SPECIFICATION forming part of Letters Patent No. 394,311, dated December 11, 1888.

Application filed August 31, 1888. Serial No. 284,278. (No model.)

To all whom it may concern:

Be it known that I, THOMAS SURTEES, a citizen of the United States, residing at Middleport, in the county of Meigs and State of Ohio, have invented a new and useful Improvement in Wagon-Jacks, of which the following is a specification.

My invention relates to improvements in wagon-jacks; and it consists in certain novel features hereinafter described and claimed.

In the accompanying drawings, Figure 1 is a perspective view of my improved jack. Fig. 2 is a central vertical section. Fig. 3 is a similar view taken at right angles to Fig. 2.

Referring to the drawings by letter, A designates the casing of my improved wagon-jack, and B designates the lifting-bar, mounted in the casing and projecting through a slot, C, in the upper end thereof. Within the casing the lifting-bar is enlarged and provided with a longitudinal slot, D, as shown.

E designates the driving-shaft journaled in the sides of the casing and extending through the longitudinal slot of the lifting-bar. One end of this shaft extends beyond the sides of the casing and is provided with a crank-handle, F, as shown. Within the casing, near one end, the shaft E is provided with a pinion, G, which meshes with a gear-wheel, H, mounted on a transverse shaft, I, journaled in the sides of the casing below the shaft E, and extending through the slot of the lifting-bar, as shown. This shaft I is further provided with a pinion, J, which meshes with the gear-teeth K, formed on one of the walls of the longitudinal slot D of the lifting-bar, as clearly shown.

L designates a pawl pivoted at its lower end to the bottom of the casing, and having its upper end engaging the gear-wheel H and adapted to lock the same against movement. This pawl L is controlled by an arm, M, pivoted thereto and extending outward through a slot, N, in the side of the casing.

In operation the upper end of the lifting-bar is placed under the axle of the wagon and the crank-handle F then rotated, so that motion will be imparted to the shaft E and the pinion G, and communicated by the same

and the gear-wheel H and shaft I to the pinion J. The pinion J meshes with the rack-teeth K on the lifting-bar and lifts the same, causing the lifting-bar to rise through the casing, thereby raising the axle. The pawl L automatically yields to the upward motion of the teeth of the gear-wheel H, so that the lifting-bar can be steadily raised, but slips into the spaces between the adjacent teeth in the event of the gear-wheel making any backward movement. When it is desired to lower the lifting-bar, the crank-handle is released and the arm M is pushed inward, thereby releasing the pawl L from engagement with the gear-wheel H, when the lifting-bar will descend of its own weight.

My device is very simple and efficient, and as all of the working parts are inclosed by the casing the liability of damage thereto is reduced to a minimum. While I have described my device as intended for use as a wagon-jack, it is equally as well adapted for lifting all heavy articles.

Having thus described my invention, what I claim, and desire to secure by Letters Patent, is—

1. The combination of the casing, the longitudinally-slotted lifting-bar mounted therein and provided with rack-teeth on one side of the slot, the transverse shaft journaled in the casing and having the pinion meshing with the rack-teeth of the lifting-bar, and mechanism for rotating said shaft, as set forth.

2. The combination of the casing, the lifting-bar mounted therein, the transverse shaft I, journaled in the sides of the casing and having a pinion geared to the lifting-bar, the wheel H on said shaft, mechanism for rotating said shaft, the pawl pivoted at its lower end to the casing and having its upper end engaging the wheel H, and the arm M, pivoted to pawl and projecting through the outer side of the casing, as set forth.

3. The herein-described jack, comprising the casing, the lifting-bar mounted therein and having the rack-teeth K, the driving-shaft journaled in the sides of the casing and provided with the crank-handle F, the

pinion G on the driving-shaft, the shaft I, journaled in the sides of the casing below the driving-shaft, the wheel H on the said shaft I, meshing with the wheel G, the pinion J on said shaft, meshing with the rack-teeth K, and the pawl L, pivoted in the casing and engaging the wheel H, as specified.

In testimony that I claim the foregoing as my own I have hereto affixed my signature in presence of two witnesses.

THOMAS SURTEES.
